UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Continuation of application Serial No. 688,207, filed January 24, 1924. This application filed May 18, 1926. Serial No. 109,869.

My invention relates to railway signaling apparatus, and particularly to apparatus of the type comprising roadside signals controlled by track circuits which are responsive 5 to the presence of trains on the track.

The present application is a continuation of my co-pending application, Serial No. 688,207, filed January 24, 1924, for railway signaling apparatus, in so far as the subject- 10 matter common to the two is concerned.

I will describe two forms of signaling apparatus embodying my invention, and will then point out the novel features thereof in claims.

15 In the accompanying drawings, Figs. 1 and 2 are diagrammatic views showing two forms of railway signaling apparatus embodying my invention.

Referring first to Fig. 1, the reference 20 characters 1 and 1^a designate the track rails of a stretch of railway track over which traffic normally moves in the direction indicated by the arrow. These track rails are divided, by means of insulated joints 2, into 25 a plurality of successive track sections A—B, B—C, etc.

Each track section is provided with a 30 suitable trackway signal. As here shown each signal comprises three indicators such as signal lamps, designated by the reference characters G, Y and R with exponents corresponding to the location and arranged when energized to indicate "proceed", "caution", and "stop", respectively.

35 Each track section is also provided with five thermo-sensitive relays designated by the reference characters H, F, J, K, and L, with exponents corresponding to the locations. Each such thermo-sensitive relay 40 comprises a heater 8 and an element 9 of thermo-sensitive material, that is, material which has the characteristic of varying its electrical resistance in response to variations in the temperature of the element. Each ther-

45 mo-sensitive element 9 is electrically insulated from the associated heater 8 but is subjected to variations in the temperature of such heater. The parts are so proportioned 50 that the resistance of each thermo-sensitive element 9 is comparatively high when the associated heater is de-energized, but that when the associated heater is energized, the temperature of the thermo-sensitive element

is increased and the resistance of the element is reduced to a comparatively low 55 value.

Referring particularly to the apparatus located at point A, the right-hand terminal of the heater 8 of thermo-sensitive relay J^A and the left-hand terminal of heater 8 of thermo-sensitive relay K^A are connected together at common terminal d. This common terminal d is connected, through heater 8 of relay L^A, with rail 1^a of the section to the left of point A. The left-hand terminal of heater 8 of relay J^A is connected with rail 1 of this section through the medium of a device 4 which permits current to flow through the heater of relay J^A in only one direction. This device comprises a uni-directional current carrying device or asymmetrical unit 60 of any desired form and may conveniently be a copper oxide asymmetrical unit such as described in an application for United States Letters Patent, Serial No. 1,111, filed 65 January 7, 1925, by Lars O. Grondahl for uni-directional current carrying devices. The right-hand terminal of heater 8 of relay K^A is connected with rail 1 through an asymmetrical unit 5. It should be noticed 70 that unit 5 is oppositely disposed with respect to unit 4, that is, these two units conduct most readily in opposite directions and hence, when rail 1 is positive with respect to rail 1^a, current flows through the heaters 75 of relays J^A and L^A, whereas, when rail 1^a is positive with respect to rail 1, current flows through the heaters of relays K^A and L^A.

Energy is supplied to the apparatus at 90 each location from a line transformer designated by the reference character T with a suitable exponent and having a primary winding 10 constantly supplied with alternating current from some suitable source 95 such as an alternator D, over line wires 3 and 3^a.

When relay J^A is energized, lamp G^A is 100 energized, current passing from secondary 13 of transformer T^A, through wire 16, heater 8 of relay H^A, wire 17, thermo-sensitive element 9 of relay J^A, wire 18, lamp G^A, and wires 19 and 20 back to secondary 13 of transformer T^A. Under this condition a proceed 105 indication is displayed at location A. When relay K^A is energized, lamp Y^A is lighted to

display a caution indication, current then flowing from secondary 13 of transformer T^A , through wire 16, heater 8 of relay H^A , wire 17, thermo-sensitive element 9 of relay K^A , wire 21, lamp Y^A , and wires 19 and 20 back to secondary 13 of transformer T^A . It will be noticed that when either indicator G^A or Y^A is energized, relay H^A is also energized.

16 Lamp R^A is provided with a circuit which passes from secondary 12 of transformer T^A , through wires 22 and 23, resistance 24, wire 25, lamp R^A , wire 26, heater 8 of relay F^A , and wire 27 back to secondary 12 of transformer T^A . This circuit is so adjusted and proportioned that lamp R^A is normally energized. When relay H^A is energized, however, current flows from secondary 11 of transformer T^A , through wire 23, resistance 24, wire 28, thermo-sensitive element 9 of relay H^A , and wire 29 back to secondary 11 of transformer T^A . The parts are so arranged and proportioned that the voltage drop in resistance 24 due to current flowing over this circuit is equal in magnitude and opposite in direction to the electromotive force applied to lamp R^A by secondary 12. It follows that when relay H^A is energized, the electromotive force applied to lamp R^A is neutralized by the voltage drop in resistance 24 and lamp R^A is therefore de-energized. But I have already explained that relay H^A is energized when either lamps G^A or Y^A is energized, and it is therefore obvious that when either lamp G^A or Y^A is lighted, lamp R^A is extinguished.

17 Relays L^A and F^A control the supply of track circuit current to section A—B in the following manner. The right-hand terminal of winding 14 of transformer T^A and the left-hand terminal of winding 15 of this transformer are connected, by wire 32, with rail 1^a of section A—B. The left-hand terminal of winding 14 is connected with rail 1^a of section A—B, through wire 30, thermo-sensitive element 9 of relay L^A , wire 31, and an asymmetrical unit 6, to rail 1. The right-hand terminal of winding 15 is connected, through wire 33, thermo-sensitive element 9 of relay F^A , wire 34, and asymmetrical unit 7 to rail 1. Units 6 and 7 are similar to units 4 and 5 and it will be clear from the drawing that when relay L^A is energized, as when lamp G^A or Y^A is energized, current is supplied to section A—B by winding 14. Due to unit 6, however, current can flow in one direction only through this circuit and rail 1 is therefore positive with respect to rail 1^a. Under these conditions, current of what I shall term "normal relative polarity" is supplied to section A—B. Similarly, when relay F^A is energized, as when lamp R^A is lighted, current is supplied to section A—B by winding 15, but under this condition rail 1^a is positive with respect to rail 1. Under

these conditions current of what I shall term "reverse relative polarity" is supplied to section A—B.

As shown in the drawing, a train, indicated diagrammatically at V , occupies the section to the left of A. Current is therefore shunted away from the relays J^A and K^A , and relays J^A , K^A and L^A are de-energized. As a result, relay H^A is de-energized, so that lamp R^A is lighted and relay F^A is energized. A stop indication is therefore displayed at point A, and track circuit current of reverse relative polarity is supplied to section A—B by winding 15 of transformer T^A . Relay K^B is therefore energized and relay L^B is also energized, but relay J^B is de-energized. As a result, lamp Y^B is energized and a caution indication is displayed at point B. The energization of relay K^B also energizes relay H^B so that lamp R^B is de-energized but relay F^B is de-energized. Track circuit current of normal relative polarity is therefore supplied to section B—C from winding 14 of transformer T^B . This track circuit current flows through heaters 8 of relays L^C and J^C and energizes these relays but relay K^C is de-energized. Lamp G^C is therefore energized and relay H^C is also energized. It follows that lamp R^C and relay F^C are both de-energized. A proceed indication is therefore displayed at point C and track circuit current of normal relative polarity is supplied to the track section to the right of point C by winding 14 of transformer T^C .

Referring now to Fig. 2, the apparatus is similar to that described for Fig. 1 except that the thermo-sensitive relays J , K , F and H are constructed so that the heater 8 of each relay is in electrical contact with the thermo-sensitive element 9 of such relay. When the heater is energized therefore the current can flow through the thermo-sensitive element to the heater of the relay.

The heater 8 of thermo-sensitive relays J and K for each section are connected in parallel across the rails adjacent the entrance end of the corresponding section through the asymmetrical units 4 and 5 as in Fig. 1, but the common terminal d of these heaters is connected directly with the rail 1^a instead of through the heater 8 of a relay L as in the preceding figure. Referring particularly to the apparatus located at point A, the circuit for lamp G^A may be traced from secondary 11 of transformer T^A , through wire 36, lamp G^A , wire 43, thermo-sensitive element 9 and heater 8 of relay J^A , wires 39, 40 and 41, heater 8 of relay H^A , wire 42, and resistance 24 back to secondary 11 of transformer T^A . This circuit is closed only when relay J^A is energized. When relay K^A is energized current flows from secondary 11 of transformer T^A , through wires 36 and 37, lamp Y^A , wire 38 thermo-sensitive element 9 and

- heater 8 of relay K^A , wires 39, 40 and 41, heater 8 of relay H^A , wire 42, and resistance 24 back to secondary 11 of transformer T^A . It follows that lamp G^A or lamp Y^A is energized according as relay J^A or relay K^A , respectively, is energized. When either of these lamps is energized, current is supplied to the heater 8 of relay H^A so that this relay is energized.
- 10 The circuit for lamp R^A passes from secondary 12 of transformer T^A , through wire 44, lamp R^A , heater 8 of relay F^A , wire 46, a portion of resistance 24, and wire 60 back to secondary 12 of transformer T^A . The parts 15 are so proportioned that when current is being supplied to either of the lamps G^A or Y^A the potential drop across the portion of resistance 24 which is included in the circuit for lamp R^A is equal in magnitude and opposite in direction to the electromotive force supplied by secondary 12 of transformer T^A . When either of lamps G^A or Y^A is lighted, then, no current flows in the circuit for lamp R^A and this lamp and relay F^A are then both 20 de-energized. When relays J^A and K^A are both de-energized, however, so that no current flows from secondary 11 through resistance 24, the electromotive force supplied by secondary 12 of transformer T^A supplies a 25 current to the circuit of lamp R^A which energizes this lamp and the heater 8 of relay F^A .
- The left-hand terminal of secondary 15 of transformer T^A is constantly connected with the right-hand terminal of secondary 14 and 30 is also connected by means of wire 51 with rail 1^a of section A—B. The right-hand terminal of secondary 15 is connected through wire 48, asymmetrical unit 7, wire 49, thermo-sensitive element 9 of heater 8 of relay H^A and wires 41, 40 and 50 to the rail 1 of 35 section A—B. It follows that when relay H^A is energized, current of normal relative polarity is supplied to the rails of section A—B. track, means for at times supplying said stretch with track circuit current of one relative polarity or the other, thermo-sensitive relays connected with said stretch and responsive to the relative polarity of such track circuit current, and traffic governing means controlled by said relays.

4. In combination, a forward and rear section of railway track, an indicator for said forward section arranged to be energized when such forward section is occupied, means for supplying said rear section with track circuit current of one relative polarity when said indicator is energized, a thermo-sensitive relay and an asymmetrical unit for said rear section responsive to such current, and traffic governing means for said rear section controlled by said relay and by said unit.

20. 5. In combination, a stretch of railway track, means responsive to traffic conditions in advance for supplying said stretch with track circuit current of one relative polarity or the other, a thermo-sensitive relay connected with said stretch, an asymmetrical unit interposed between said stretch and said relay, and traffic governing means controlled by said relay.

6. In combination, a stretch of railway track, two sources of energy, two thermo-sensitive relays one for connecting each said source with the rails of the stretch when the associated relay is energized, means for energizing one said relay or the other in accordance with traffic conditions, an asymmetrical unit interposed between said stretch and one said source, a second oppositely disposed asymmetrical unit interposed between said stretch and the other said source, and traffic governing means responsive to the relative polarity of the current in said stretch.

7. In combination, a stretch of railway track, two thermo-sensitive relays each having a heater, means for connecting one terminal of each heater to one rail of said stretch and for connecting the other terminal of each heater to the other rail, an asymmetrical unit interposed between one heater and one rail of said stretch, an oppositely disposed asymmetrical unit interposed between the remaining heater and one rail of the stretch, and traffic governing means controlled by said thermo-sensitive relays.

55. 8. In combination, a stretch of railway track, means for supplying said stretch with track circuit current of one relative polarity or the other in accordance with traffic conditions, a thermo-sensitive relay, means including an asymmetrical unit for connecting said thermo-sensitive relay with said stretch, and traffic governing means controlled by said relay.

65. 9. In combination, a stretch of railway track, two thermo-sensitive relays, an asym-

metrical unit associated with each said relay, and means controlled by said relays and by said asymmetrical units for supplying said stretch with track circuit current of one relatively polarity or the other in accordance with traffic conditions.

10. In combination, a stretch of railway track, two thermo-sensitive relays, an asymmetrical unit associated with each said relay, means controlled by said relays and by said asymmetrical units for supplying said stretch with track circuit current of one relative polarity or the other in accordance with traffic conditions, and traffic governing means responsive to the polarity of such current.

11. In combination, a stretch of railway track, two thermo-sensitive relays, an asymmetrical unit associated with each such relay, and means controlled by said relays and by said asymmetrical units for supplying said stretch with track circuit current of one relative polarity or the other in accordance with traffic conditions.

12. In combination, a stretch of railway track, means for supplying said stretch with track circuit current of one relative polarity or the other in accordance with traffic conditions, a thermo-sensitive relay, means including an asymmetrical unit for connecting said thermo-sensitive relay with said stretch, an indicator controlled by said thermo-sensitive relay, and a second indicator arranged to be de-energized when said first indicator is energized.

13. In combination, a stretch of railway track, means for supplying said stretch with track circuit current of one relative polarity or the other in accordance with traffic conditions, a trackway signal comprising a plurality of indicators, a thermo-sensitive relay for controlling one said indicator, means including an asymmetrical unit for connecting said relay with said stretch, a second thermo-sensitive relay for controlling the second said indicator, and means including an asymmetrical unit oppositely disposed with respect to said first unit for connecting said second thermo-sensitive relay with the stretch.

14. In combination, a stretch of railway track, means for supplying said stretch with track circuit current of one relative polarity or the other in accordance with traffic conditions, a trackway signal comprising a plurality of indicators, a thermo-sensitive relay for controlling one said indicator, means including an asymmetrical unit for connecting said relay with said stretch, a second thermo-sensitive relay for controlling the second said indicator and means including an asymmetrical unit oppositely disposed with respect to said first unit for connecting said second thermo-sensitive relay with the stretch, and a third indica-

tor arranged to be de-energized when either said first or said second indicator is energized.

15. In combination, a stretch of railway track, a trackway signal responsive to traffic conditions, means including a thermo-sensitive relay and an asymmetrical unit for supplying track circuit current of one characteristic to said stretch when said signal is displaying one indication but not when said signal is displaying a different indication, and traffic governing means responsive to said current.

16. In combination, a stretch of railway track, a trackway signal responsive to traffic conditions, and means including a thermo-sensitive relay and an asymmetrical unit for supplying track circuit current of one relative polarity to said stretch when the signal is displaying one indication and for supplying track circuit current of the other relative polarity to the stretch when the signal is displaying a different indication.

25. 17. In combination, a stretch of railway track, means for supplying said stretch with track circuit current of one relative polarity or the other in accordance with traffic condition, two thermo-sensitive relays each comprising a heater, means for connecting said heaters in parallel across the rails of said stretch, two asymmetrical units one interposed between each heater and one rail of the stretch, and traffic governing means controlled by said thermo-sensitive relays.

18. In combination, a stretch of railway track, means for supplying said stretch with track circuit current of one relative polarity or the other in accordance with traffic conditions, two thermo-sensitive relays each comprising a heater, means for permitting current from said stretch to flow only in one direction through one heater and only in the other direction through the remaining heater, and traffic governing means controlled by said thermo-sensitive relays.

19. In combination, a stretch of railway track, means for supplying said stretch with track circuit current of one relative polarity or the other in accordance with traffic conditions, two thermo-sensitive relays each comprising a heater, means for connecting said heaters in parallel across the rails of said stretch, two asymmetrical units one interposed between each heater and one rail of the stretch, and two indicators one controlled by each said thermo-sensitive relays.

20. In combination, a stretch of railway track, means for supplying said stretch with track circuit current of one relative polarity or the other in accordance with traffic conditions, two thermo-sensitive relays each comprising a heater, means for connecting said heaters in parallel across the rails of said

stretch, two asymmetrical units one interposed between each heater and one rail of the stretch, two indicators one controlled by each said thermo-sensitive relay, and a third indicator arranged to be de-energized when either of said first two indicators is energized.

21. In combination, a stretch of railway track, means for supplying said stretch with track circuit current of one relative polarity or the other in accordance with traffic conditions, two thermo-sensitive relays each comprising a heater, means for connecting said heaters in parallel across the rails of said stretch, two asymmetrical units one interposed between each heater and one rail of the stretch, two indicators one controlled by each said thermo-sensitive relay, a third thermo-sensitive relay controlled by said first two thermo-sensitive relays, and a third indicator controlled by said third thermo-sensitive relay.

22. In combination, a stretch of railway track comprising a forward and a rear section, means for supplying said forward section with track circuit current of one relative polarity or the other in accordance with traffic conditions, a first and a second thermo-sensitive relay each comprising a heater, connected across the rails of said forward section, two asymmetrical units oppositely connected in series with said heaters respectively, a third and a fourth thermo-sensitive relay; a circuit for the heater of said third relay including a source of energy, a resistance, and the thermo-sensitive elements of said first and second relays in parallel; a circuit for the heater of said fourth relay including a second source of energy and a portion of said resistance; and means for supplying the rails of said rear section with current of one relative polarity or the other according as said third relay or said fourth relay is energized.

23. In combination, a stretch of railway track comprising a forward and a rear section, means for supplying said forward section with track circuit current of one relative polarity or the other in accordance with traffic conditions, a first and a second thermo-sensitive relay each comprising a heater connected across the rails of said forward section, two asymmetrical units oppositely connected in series with said heaters respectively, a third and a fourth thermo-sensitive relay; a circuit for the heater of said third relay including a source of energy, a resistance, and the thermo-sensitive elements of said first and second relays in parallel; a circuit for the heater of said fourth relay including a second source of energy and a portion of said resistance; a third source of energy, means for supplying current of one relative polarity to the rails of said rear section from said third source when

said third relay is energized, a fourth source of energy, and means for supplying current of the opposite relative polarity to the rails of such rear section when said fourth relay is energized.

24. In combination, a stretch of railway track comprising a forward and a rear section, means for supplying said forward section with track circuit current of one relative polarity or the other in accordance with traffic conditions, a first and a second thermo-sensitive relay each comprising a heater connected across the rails of said forward section, two asymmetrical units oppositely connected in series with said heaters respectively, a third and a fourth thermo-sensitive relay, a transformer comprising a primary constantly supplied with alternating current and four secondaries; a circuit for the heater of said third relay including one of said secondaries, a resistance and the thermo-

sensitive elements of said first and second relays in parallel; a circuit for the heater of said fourth relay including a second secondary of said transformer, and a portion of said resistance, means for connecting the common terminal of the third and fourth transformer secondaries with one rail of said rear section, means including an asymmetrical unit and the thermo-sensitive element of said third relay for connecting the free terminal of said third secondary with the other rail of the rear section, and means including a second oppositely disposed asymmetrical unit and the thermo-sensitive element of the fourth relay for connecting the free terminal of the fourth transformer secondary with such other rail of said rear section.

In testimony whereof I affix my signature,

LARS O. GRONDAHL.
